UNITED STATES PATENT OFFICE

JOHN R. TEECY, OF ELLSWORTH, KANSAS.

STATISTIC GAME-CARD.

1,193,628.

Specification of Letter Patent

Patented Jan. 5, 1915.

Application filed March 26, 1914. Serial No. 827,426.

To all whom it may concern:

Be it known that I, JOHN R. TEECY, a citizen of the United States, residing at Ellsworth, in the county of Ellsworth and State of Kansas, have invented certain new and useful Improvements in Statistic Game-Cards, of which the following is a specification.

My invention relates to cards for use in playing games and while intended to furnish amusement and entertainment, it is my purpose to also provide cards which shall be instructive.

My invention comprises a deck or pack of playing-cards upon each of which is depicted the data relating to a single State or Territory, my purpose being to provide a card for each State, Territory or possession of the United States.

For the purpose of illustrating the manner of constructing or arranging the cards of the game constituting my invention, I have shown in the accompanying drawing a plan view of a card having depicted thereon the data for the State of Ohio, the other cards being formed in a similar manner.

In the center of the card is an outline of the particular State or Territory and preferably having imprinted thereon a representation of the seal corresponding thereto. While I have shown the map on the accompanying drawing occupying a small space, it is to be understood that it may, if desired, occupy substantially all of the space or area

between the marginal columns. I prefer to tint the portion of the card inclosed within the boundary line of the State in a color which will form a proper background so that any printing or lettering thereon will be distinct.

Upon the margins are given the names of the adjacent boundaries upon the several sides or borders of the State. Within the margins upon either side are arranged a series of geometrical figures, four different orders being shown, forming a column extending from the top to the bottom margin, those on the right being in one color and those upon the left being another color. By the side of each of these geometrical figures and

extending inwardly toward the center in the space between the columns, is a word referring to some physical characteristic, as lakes, rivers, etc., political divisions, as counties or cities or some data relating to the inhabitants, as Congressmen, soldiers,

farmers, etc. In the column of figures on the right are numerals giving the number corresponding to the adjacent word and in the left-hand column are figures corresponding to the per cent of the population referred to by the adjacent word. At the bottom of each column is a numeral corresponding to the total of the numbers in the column. Other data, as the number of square miles, the total population, etc., may be given in the central space or body of the card, as indicated. The data or facts stated may, of course, vary to suit the special conditions of the State or Territory to which the card relates. At some convenient point on the card I place the word "trumps" and underneath indicate one of the geometrical figures in either the color of the right-hand or that of the left-hand figures.

The manner of playing with these statistic cards is very similar to other game cards. Any convenient number of persons can play as will be understood. For the purpose of illustrating some of the ways in which these cards may be played I will briefly outline certain games. A game designated "Building the U. S. Map" may be played as follows:—The pack of cards having been shuffled in the ordinary way, three or five cards are dealt to each player and the one on the right of the dealer may play first, using any card in his hand. The player to his right then plays but must place a card that joins upon one of the four sides of the card first played. Thus, if, for instance, the first card played represented the State of Kansas, then the second player must play a card corresponding to either Colorado, Nebraska, Missouri or Oklahoma. If he has none of these cards, he must draw from the deck until he obtains the proper card. This operation is repeated by each player until all of the cards have been drawn. After the deck has been exhausted the player who plays all of his cards first is the winner of the game, scoring a number of points equal to the totals on the cards left in the hands of his opponent as in the well known game of dominoes.

A simple game may be played with the "totals" indicated on the cards, in which the player consults the total on his card to ascertain its relative value and to know whether it is large enough to capture his opponent's card. It is evident that the

players may elect to use the totals upon either side of the card or possibly the sum of the totals upon both sides.

As previously mentioned, each card carries an indication of the geometrical figure and color which may be trumps, and in games where the trump card is turned up by the dealer, it is done in the ordinary way by turning over a card after the cards have been dealt. From the above description the manner of using these cards will be understood by those familiar with card games, although, as is usual, a set of rules and instructions in regard to the manner of playing various games with these cards will ordinarily accompany them.

While I have described in detail the arrangement shown in the accompanying drawing for the purpose of disclosing an embodiment of my invention, it is to be understood that immaterial changes may be made therein without departing from the scope of my claims. Thus, I may use other geometrical figures, and employ any desired set of statistics, as commercial, political, educational, social, religious, etc., and the individual cards may describe or relate to a single State or a number or group of States and to other countries than the United States.

I claim:

1. A game card, comprising a central space or body portion containing a representation of the outline or boundary of a State or country and a series of words or terms relating to features or facts pertaining to said State or country, and a series of geometrical figures arranged in a column upon opposite sides of said central space and having thereon numerals indicating data corresponding to one of said words or terms in juxtaposition thereto.

2. A game card, comprising a central space or body portion containing a representation of the outline or boundary of a State or country and a representation of the seal thereof and a series of words or terms relating to features or facts pertaining to said State or country, a series of geometri-

cal figures arranged in a column upon opposite sides of said central space and having thereon numerals indicating data corresponding to one of said words or terms in juxtaposition thereto, and a numeral at the bottom of each column indicating the total of the figures in the column.

3. A game card, comprising a central space or body portion containing a representation of the outline or boundary of a State or country and a representation of the seal thereof and a series of words or terms relating to features or facts pertaining to said State or country, a series of geometrical figures arranged in a column upon opposite sides of said central space and having thereon numerals indicating data corresponding to one of said words or terms in juxtaposition thereto, the figures in the opposite columns being in different colors, and a numeral at the bottom of each column indicating the total of the figures in the column.

4. A game card, comprising a central space or body portion containing a representation of the outline or boundary of a State or country and a series of words or terms relating to features or facts pertaining to said State or country, a series of conventional figures arranged in a column upon opposite sides of said body portion, the figures in the opposite columns being in different colors and having thereon numerals indicating data corresponding to one of said words or terms in juxtaposition thereto, a trump figure corresponding in color and design to one or more of the figures in one of said columns in the body portion, and a word or name upon each margin indicating the corresponding State or physical body bounding the adjacent side of said State or country.

In testimony whereof I affix my signature in presence of two witnesses.

JOHN R. TERCY.
